DESIGN FOR A TUMBLER

Donald Deskey, New York, N. Y., assignor to Libbey Glass Company, Toledo, Ohio, a corporation of Ohio

Application January 29, 1936, Serial No. 60,870

Term of patent 3½ years

To all whom it may concern:

Be it known that I, Donald Deskey, a citizen of the United States, residing in New York city, in the county of New York and State of New York,
have invented a new, original, and ornamental Design for a Tumbler, of which the following is a specification, reference being had to the accompanying drawing, forming part thereof.

The drawing is a side elevational view of a tumbler showing my design.

The tumbler is of conventional round contour.

I claim:

The ornamental design for a tumbler, substantially as shown and described.

DONALD DESKEY.
